(57) **CLAIM**

We claim the ornamental design for a control console for a vehicle, as shown and described.

DESCRIPTION

FIG. 1 is a side perspective view of the control console for a vehicle showing our new design;

FIG. 2 is a top view thereof;

FIG. 3 is a right side view thereof;

FIG. 4 is a left side view thereof;

FIG. 5 is a front view thereof;

FIG. 6 is a rear view thereof;

FIG. 7 is a bottom view thereof; and,

FIG. 8 is a rear perspective view thereof.

In the drawings, the broken lines depict portions of the article that form no part of the claim.
